UNITED STATES PATENT OFFICE.

ORA A. COLEY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed December 17, 1921. Serial No. 523,212.

To all whom it may concern:

Be it known that I, ORA A. COLEY, a citizen of the United States, and a resident of Irwin, in the county of Westmoreland and State of Pennsylvania, have invented a new and useful Improvement in Electric Furnaces, of which the following is a specification.

My invention relates to electrically heated apparatus, and particularly to electric-resistance furnaces, and it has for its object to provide a relatively simple and inexpensive mounting for the resistor of an electric furnace.

My invention comprises a plurality of sets of refractory supporting members, the ends of which project into the furnace chamber and are so shaped as to form a groove between each two adjacent and contiguous members having an enlarged inner portion, within which is located a member of U form. A relatively heavy and unyielding preformed resistor member is supported by the members of U shape, the resistor member being sufficiently heavy to be substantially self-supporting between the sets of refractory members. Embodying means is provided on the refractory members to lock the members of U-shape in their proper operative positions.

In the single sheet of drawings,

Figure 1 is a view, in vertical cross section, on a line I—I of Fig. 2, of an electric furnace comprising a device embodying my invention;

Fig. 2 is a partial longitudinal cross-sectional view taken on the line II—II of Fig. 1;

Fig. 3 is a view, in end elevation, of a refractory supporting member;

Fig. 4 is a view, in front elevation, of the member illustrated in Fig. 3, and

Figs. 5, 6 and 7 are top plan, front, and end elevational views of a bushing comprising a part of the device embodying my invention.

An electric-resistance furnace 10 comprises an outer metallic skeleton or framework 11 having a plurality of supporting members 12. An outer lining 13 comprises a plurality of suitable bricks or blocks of a heat-insulating material. An inner lining 14 comprises a plurality of bricks or blocks of a suitable high-temperature-resisting material, the bricks or blocks being so disposed

and combined as to form a furnace chamber 15 of any suitable or desired contour and dimensions.

The inner lining 14 is built up in spaced-apart sections to provide a plurality of spaces 16 therebetween. A plurality of relatively narrow refractory members 17, of substantially T-shape, are located in the spaces 16, the bricks adjacent the spaces 16 being formed with overhanging shoulders 18 to suitably hold the refractory members 17 in their proper operative positions in the furnace. The inner end of each of the members 17 is so shaped that a groove 19 is formed between each two adjacent members, the said groove having an enlarged inner portion and a relatively narrow outer portion. While I illustrate a plurality of refractory members 17 as constituting the supporting members, I may employ a single member of the proper dimensions, and form therein a plurality of open slots or grooves 18, substantially as hereinbefore described.

A relatively short bushing 19, of substantially U-form is located in the enlarged inner portions of a groove 18, the outer diameter of the bushing 19 being slightly less than the diameter of the substantially circular inner portion of the groove 18. In order to hold the bushing 19 in its position in the groove 18, small overhanging or flange portions 21 are provided adjacent the sides of each of the members 17, the length of the bushing 19 being less than the distance between the flange portions 21 to permit of locating it therebetween. The bushings may be made of a suitable refractory material or of a suitable metal, such as nichrome.

A resistor member 22 comprises a plurality of substantially straight and parallel extending end-connected convolutions of a rod or bar which is preformed to substantially the form illustrated particularly in Fig. 2. The dimensions of the opening in the member 19 is such that a member may be placed on or over a portion of a convolution of the resistor member to operatively engage and support the same when the member 19 is placed in one of the grooves 18.

The method of mounting the resistor member in the furnace is substantially as follows:

A preformed resistor member 22 may be located in the grooves 18, being moved thereinto laterally of the furnace and of the con-

volutions of the resistor member. Bushings 19 may then be placed upon the convolutions immediately adjacent the spaced-apart sets of refractory members 17, and if the resistor member is so held as to be substantially coaxial with the enlarged portion of the groove 18, the bushings 19 may be moved into the grooves 18 in such positions as to close the open portions of such groove and thus maintain the resistor member in its proper operative position relatively to the supporting member 17.

If it is desired to leave the bushings 19 in the grooves 18 when removing the resistor, it is only necessary to turn the bushings through an angle of substantially 180° by any suitable means, which movement opens the groove and permits of removing the resistor member.

20. The device embodying my invention provides a relatively simple means for mounting a relatively heavy and unyielding pre-formed resistor member in spaced-apart sets of relatively narrow refractory supporting members. The device is of particular value when it is desired to mount a resistor member of the character described in the roof of a furnace chamber but it may also be employed to maintain a resistor member in 25 proper operative position in the side walls of a furnace.

This application is closely related to a pending application of Thomas A. Reid, Serial No. 529,004 filed Jan. 13, 1922, and 30 assigned to the Westinghouse Electric & Manufacturing Company.

Various modifications may be made in the device embodying my invention without departing from the spirit and scope thereof, 40 and I desire that only such limitations shall be placed thereon as are imposed by the prior art or are specifically set forth in the appended claims.

I claim as my invention:—

45. 1. A resistor-supporting means comprising a pair of abutting refractory members, each member having a groove in its opposing surface composed of an inner relatively deep portion and an outer shallow portion, and a member of substantially U-form located in the opposing deeper portions of the co-operating grooves.

2. In a resistor-supporting means, in combination, a plurality of alined refractory members, each member having a slot in its contiguous faces near one end of the member, of such shape that the adjacent slots form an open groove having an enlarged inner portion, a member of substantially U-form located in the enlarged inner portion for operatively engaging a resistor member, and embodying means in said refractory members for holding said member of U-form in said groove.

65. 3. In a resistor-supporting means, in com-

bination, a plurality of alined contiguous refractory members, each member having a slot in its contiguous faces near one end of the member, of such shape that the adjacent opposing slots combine to form an open 70 ended groove having an enlarged inner portion, a member of substantially U-form located in the enlarged inner portion of said groove for operatively engaging a resistor member and embodying means in said refractory members for holding said members of U-form in said grooves while permitting 75 longitudinal movement of a resistor member supported thereby.

4. In a heating element, in combination, 80 a plurality of spaced-apart sets of alined abutting refractory members, the inner end of each of said members being so shaped as to form a groove between two adjacent members having an enlarged inner portion, 85 a relatively heavy and unyielding resistor member preformed to comprise a plurality of substantially parallel-extending end-connected convolutions, a portion of a convolution being located in said enlarged 90 inner portion of a groove and the resistor extending between and beyond said sets of refractory members, a member of substantially U-form located in said enlarged portion of said groove and operatively engaging 95 said resistor to support the same, and embodying means in each of said abutting refractory members for holding said member of U-form in said groove.

5. In an electric-resistance furnace, in 100 combination, a plurality of walls enclosing a furnace chamber, a plurality of spaced-apart sets of alined abutting relatively narrow refractory members supported by said furnace walls, the inner end of 105 said members projecting into said furnace chamber and being so shaped as to form a groove between two adjacent members having an enlarged inner portion, a relatively heavy resistor member preformed to comprise a plurality of end-connected convolutions, a part of each convolution being located in the enlarged portion of a groove, the remainder extending between and beyond 110 said sets of refractory members and 115 being substantially self-supporting, a member of U-shape located in said groove and operatively engaging said resistor member and embodying means on said refractory members for holding said member of 120 U-shape in said groove while permitting the expansion and contraction of said resistor member.

6. In an electric-resistance furnace, in combination, a plurality of walls enclosing 125 a furnace chamber, a relatively heavy resistor member preformed to comprise a plurality of end-connected convolutions, a plurality of spaced-apart sets of relatively narrow refractory members supported by said 130

walls and having the portions extending into the furnace chamber so shaped as to form a groove between two adjacent members having an enlarged inner portion for receiving 5 a part of a convolution of said resistor member movable thereinto laterally of said furnace, a member of substantially U-shape for holding said resistor in said enlarged portion of the groove and embodying means on

said refractory members for holding said 10 member of U-shape in said groove while permitting the expansion and contraction of said resistor member.

In testimony whereof, I have hereunto subscribed my name this 25th day of November, 1921.

ORA A. COLBY.
